UNITED STATES PATENT OFFICE.

JOSEPH G. SCHLÜCHTNER, OF BROOKLYN, NEW YORK.

AUTOMATIC HEAT-ALARM.

1,076,157.

Specification of Letters Patent.

Patented Oct. 21, 1913.

Application filed April 25, 1912. Serial No. 693,151.

To all whom it may concern:

Be it known that I, JOSEPH G. SCHLÜCHTNER, a citizen of the United States, residing at Brooklyn, in the county of Kings and

5 State of New York, have invented certain new and useful Improvements in Automatic Heat-Alarms, of which the following is a specification.

This invention has for its object to provide 10 a thermometric indicator or alarm device which may be utilized to give warning of excessive heat in various adaptations, as in buildings, in case of fire, in powder magazines and the like, in case of spontaneous combustion, or in the bearings of machines, due to friction, and which in any of the 15 adaptations to which it may thus be put will be efficient, reliable (to such a degree that it will not prematurely operate, as when moved or shaken as an incident to its use, and yet will assuredly operate when a 20 predetermined temperature is reached), simple in construction and capable of ready assembling of its parts.

25 Among the salient features of my invention are the peculiar form of its receptacle for a thermo-expansible electro-conductive fluid, such as mercury, whereby a very appreciable exposure of surface of such fluid 30 to the heat of the atmosphere, transmitted through the wall of such receptacle, is accomplished, and at the same time the said fluid is maintained more or less quiescent, notwithstanding the device may be shaken 35 or otherwise moved sufficiently so that otherwise the fluid would be caused to close the electric circuit in which the device is instituted; the peculiar form and arrangement of the terminals of the electric circuit with 40 relation to said receptacle and the circuit closing fluid; and the manner in which the various parts of the device are assembled.

I have fully illustrated the invention in the annexed drawing, wherein,

45 Figure 1 is a sectional view thereof with the electric circuit and alarm with which it is associated shown diagrammatically; Fig. 2 is a plan view of the device with the mounting *a* removed and the circuit omitted; and, 50 Fig. 3 is a sectional view on line *x*—*x* of Fig. 1.

a may be any suitable mounting. It is herein shown as having a stem *a'* for attaching it to some support, as *b*, and is 55 preferably formed of porcelain or the like,

though these details are wholly immaterial. Its body part *c* is annular, and preferably has an internal screw-thread *d*, thus forming a socket.

e is a receptacle for the mercury *f* or 60 other thermo-expansible electro-conductive liquid. It is preferably made of glass, though this is not essential; glass is preferred because it is transparent, permitting visual inspection of the interior of the receptacle, especially in assembling the parts and adjusting the apparatus to the conditions under which it is to operate. The receptacle *e* is made up of a plurality of hollow disks *g*, arranged one above the other, 65 and tubular necks *h*, preferably vertically aligned with each other and alternating and formed integral with the disks. The uppermost chamber *g* and the uppermost neck *h* have each greater vertical dimension than 70 the other disks and necks, respectively, as shown. The uppermost chamber has a throat or mouth *i* axially aligned with the necks *h*, and of somewhat larger diameter. 75

A metallic piece *j*, including a screw-threaded outer bushing *k* and a depending interior part *l*, is screwed into the socket *c*. Into the annular space existing between bushing *k* and the depending part *l* is fitted the mouth *i* of receptacle *e*, such mouth being embedded in a filling of cement *m* which, upon setting, becomes locked in place by virtue of the screw-threading of bushing *k*; the exteriorly threaded piece *j* forms a part 80 of a plug projecting from the receptacle member which is screwed into the socket member, as shown in the drawings. 85

The part *l* has its portion *n*, which depends well below the bottom of socket *c*, tapering and formed with an open end whose edge is toothed or serrated, as indicated by *o*. In the assembled relation of the parts, the points of the teeth or serrations *o* lie in a horizontal plane substantially coincident with that where the upper neck *h* merges into the upper chamber *g*, the diameter of the lower extremity of portion *n* being about equal to the internal diameter of said neck. Thus, before the mercury can enter the uppermost chamber 95 it must contact with the lower serrated end of portion *n*. 100

Axially coincident with the bushing and within the same is a metal cylindrical socket *p* having a downwardly depending wire or 110

other form of metallic extension *q* which protrudes from the lower end of the part *l* of said bushing into the uppermost neck *h*. A filling of non-electro-conductive cement or the like *r* occupies the space of part *l* and holds the socket *p* in place. To support the cement *r* upon its introduction and while setting a fiber or other non-conducting disk *s* may be jammed into the lower end of part *l*, being penetrated by the extension *q*. *t* designates an electric circuit in which is a bell or similar device *u*, one end of the wire included in said circuit being attached to a binding-post *v* on the piece *j* and the other to a binding-post *w* carried by a split plug *x* which may be removably fitted into the socket *p*.

The mercury is introduced into the receptacle *e* at a temperature which corresponds to that at which the apparatus is to operate; at such temperature, the mercury should have contact with both the serrated lower end of the part *l* of the bushing and the extension *q* of the socket *p*, so sufficient mercury is introduced to bring its top surface under the temperature-condition designated in the same horizontal plane as the tips of the serrations of part *l*. The bushing, the socket and the filling *q* of cement having been preferably first assembled, the mouth of the receptacle is embedded in the filling of cement *m*, having first, however, charged the space of the receptacle above the mercury with compressed air.

In use, should the temperature of the place or part which is to be protected exceed that predetermined the mercury will rise until, the lower end of extension *q* being submerged, it contacts with the serrated lower end of the part *l*, thus closing the circuit and sounding the alarm. The peculiar form of the receptacle plays an important part in stabilizing the mercury, since only a limited part of the mercury, *i. e.*, that directly occupying the vertical passage in the receptacle which is constituted by the series of necks *h*, is free to rise, the rest being confined by lateral recesses extending from said passage—the outlying interiors of the chambers *g*. Since the lower end of the terminal formed by part *l* extends downwardly at least as far as the plane of the upper end of neck *h*, the normally exposed surface-area of the mercury up to the moment of the closing of the circuit in the proper or contemplated performance of the device is limited, enhancing the effect of preventing such motion of the mercury, due to jarring or shocks or shaking the device. as would cause it to touch the terminal *l* and close the circuit prematurely, such as might occur, for instance, if the mercury were allowed to enter the uppermost chamber *h* before assuming the intended contact with the terminal *l* and there expose a con-

siderable surface-area. It will be understood that by forming the receptacle as a series of disk-like hollow chambers the receptacle exposes a considerable surface to the atmosphere, thereby increasing the sensitiveness of the device.

Where the receptacle is formed of a non-conducting material, such as glass, and each terminal member is independent of the receptacle, as is preferred, the reliability of the device is further insured thus: If the mere touching of the mercury with the extreme points of the serrated lower end of part *l* should not be sufficient (the end of extension *q* being already submerged in the mercury) effectively to close the circuit the mercury will work its way through the openings between the serrations until a good contact is produced. On the other hand, the lower end of part *l* being well spaced from the terminal *q* any possible adhesion of globules or particles of mercury in sufficient quantity to close the circuit is prevented. To insure the efficiency of the device, metals for the terminals *q* and *o* are employed with which mercury will not amalgamate.

Having thus fully described my invention, what I claim as new and desire to secure by Letters Patent is:—

1. In combination, a suitable receptacle, a thermo-expansible electro-conductive fluid arranged in said receptacle, an alarm, an electric circuit including the alarm and having a break therein and terminals at said break both depending into said receptacle to different depths, one surrounding the other and having downwardly extending teeth or serrations, substantially as described.

2. In combination, a suitable receptacle having an upwardly extending neck, a thermo-expansible electro-conductive fluid arranged in said receptacle, an alarm, an electric circuit including the alarm and having a break therein and terminals at said break both depending into said receptacle to different depths, one surrounding the other and having downward projections extending at least as far as the horizontal plane of the upper extremity of said neck, substantially as described.

3. In combination, a mounting, an annular metallic member forming a terminal and having an exterior hollow portion secured in the mounting and an interior depending hollow portion spaced from said exterior portion, a body of insulating material occupying the space of said interior portion, a body of cement occupying the space between said exterior and interior portions, another metallic member embedded in the body of insulating material, an alarm, an electric circuit including the alarm and having a break therein and also having its ends at said break attached to said members,

and a receptacle having a mouth embedded in said cement body, substantially as described.

4. In an apparatus of the class described, a thermo-expansible electro-conductive fluid and a hollow receptacle containing said fluid, said receptacle comprising a plurality of superposed hollow disks and relatively

limited tubular necks connecting said disks, substantially as described.

In testimony whereof I affix my signature in presence of two witnesses.

JOSEPH G. SCHLÜCHTNER.
